(57) **CLAIM**

The ornamental design for a footwear insert, as shown and described.

DESCRIPTION

FIG. 1 is a top plan view of a footwear insert showing my new design;

FIG. 2 is a bottom plan view thereof;

FIG. 3 is a bottom perspective view thereof;

FIG. 4 is a top perspective view thereof;

FIG. 5 is a top plan view thereof, in assembled condition;

FIG. 6 is a bottom plan view of FIG. 5;

FIG. 7 is a top, right perspective view of FIG. 5;

FIG. 8 is a top, left perspective view of FIG. 5;

FIG. 9 is a right side elevational view of FIG. 5;

FIG. 10 is a left side elevational view of FIG. 5;

FIG. 11 is a front elevational view of FIG. 5, partially broken away for ease of illustration; and,

FIG. 12 is a rear elevational view of FIG. 5.
